FIRE EXTINGUISHER SPRINKLER HEAD

Peter Lim, Los Angeles, Calif.

Application March 5, 1951, Serial No. 213,858

5 Claims. (Cl. 169—41)

1

My invention relates generally to pressurized, automatic vaporizing liquid sprinkler units for extinguishing fires, and more particularly to the sprinkler heads thereof.

An object of my invention is to provide a fire extinguisher sprinkler head structurally characterized by means which enables the extinguishant of the unit to be finely atomized thoroughly over a maximum area in a minimum time following release of the valve of the sprinkler head by the heat responsive fuse thereof, all so as to obtain the most efficient use possible of the unit by controlling and extinguishing a fire before same has gained any appreciable headway, thus effectively protecting the relatively large area within the extensive range of operation of the unit against damage by fire.

Another object of my invention is to provide a fire extinguisher sprinkler head of the above described character which embodies a movably mounted spray nozzle normally maintained in a retracted position within the body of the head by the valve of the latter against the internal pressure of the extinguishant, which pressure is automatically operable upon a release of the valve by the fuse, to move the nozzle to a projected position wherein the tip of the nozzle will be exposed sufficiently to be free and unobstructed by the body of the head, so as to utilize the nozzle at its maximum efficiency in discharging a finely atomized spray of extinguishant over the widest possible area, and thus obtain maximum fire protection from the unit.

With these and other objects in view, my invention resides in the combinations, arrangements and functional relationships of elements as set forth in the following specification and particularly pointed out in the appended claims.

In the accompanying drawings,

Figure 1 is a view showing partly in side elevation and partly in central, vertical longitudinal section, one form of fire extinguisher sprinkler head embodying my invention, and illustrating the set position of the head;

Figure 2 is a vertical longitudinal sectional view taken on the line 2—2 of Figure 1, and illustrating the head in released position;

Figure 3 is a horizontal sectional view taken on the line 3—3 of Figure 1;

Figure 4 is a perspective view of the atomizing spray nozzle embodied in my invention; and

Figure 5 is a perspective view of a retaining element for the nozzle.

Referring specifically to the drawings, my invention, in its present embodiment, comprises a

10 cast metal support S composed of an elongated body 10 having oppositely curved arms 11 extending therefrom at diametrically opposed points and rigidly connected by a hub 12 co-axially related to a smooth, open-ended bore 13 extending longitudinally through the body 10 and uniformly tapered to decrease in diameter towards that end which constitutes an outlet 14 bounded by annular valve seat 15.

15 Between the body 10 and the hub 12, the arms 11 form a large, generally oval shaped opening 16 for a valve 17, a cup 18, and a thermo-responsive or fusible element 19, the latter being confined tightly between the valve and cup by a pin 20 (Figure 2) fixed in the hub 12 and supporting the cup. The valve 17 is thus maintained in fluid-tight engagement with the valve seat 15, with a guide teat 21 on the valve entering the bore 13 to maintain the valve in co-axial relation to the seat, all as clearly shown in Figure 1.

20 Movable mounted in the bore 13 of the body 10 is an atomizing spray nozzle 25 in the form of a tube, the major portion of the length of which is longitudinally tapered externally as indicated at 26, to correspond with the taper of the bore 13 and to decrease in diameter towards the tip 27 of the nozzle in which is a flared outlet port 28.

25 The remaining portion of the length of the nozzle 25 is externally cylindrical as indicated at 30, and is reduced in diameter to define an annular stop shoulder 31. A retaining element 32 in the form of a ring, has an internal diameter 33 to freely receive the cylindrical portion 30 of the nozzle, and is tapered externally as indicated at 34 to enter and have a press fit in the larger end of the bore 13 so as to permanently be secured in the latter and thus co-act with the teat 21 of the valve 17 in confining the nozzle in its retracted position wherein the nozzle fits loosely in the bore 13 as shown in Figure 1.

30 Adjacent to its free end, the nozzle 25 is provided internally with an annular seat 35 for a disk 36 having helically extending slots 37 in its periphery for imparting a whirling motion to liquid discharging from the nozzle, all so as to more effectively atomize the liquid.

The body 10 is provided with external screw threads 40 to enable the body to be screwed into the threaded bore 41 of an outlet collar 42 provided on the bottom of a tank or container 43 for the pressurized liquid fire extinguishant, so as to support the sprinkler head from the container in the vertical, subtending position shown in Figures 1 and 2.

35 It will be understood that the container 43 of

which only the bottom portion is shown for the purpose of illustrating my present invention, may be anchored or suspended in an elevated position from the ceiling of a room or roof of a building, or from any suitable support over the area to be protected against fire.

The operation of the invention is as follows:

Let it be assumed that the container 43 has been charged with carbon tetrachloride and liquid carbon dioxide to approximately 90 p. si. i., and is suspended near the ceiling of a room or other enclosure to be protected. The sprinkler head embodying my invention will occupy the set position shown in Figure 1, from which it will be noted that the upper end of the retracted nozzle 25 extends above the lowest point in the container 43 so as to form a guard wall and co-act with the retaining element 32 in protecting the interior of the nozzle against any sediment accumulating on the container bottom around the nozzle, all so as to prevent clogging of the latter.

Should a fire occur, the resulting abnormal rise in temperature will cause the fuse 19 to burst and free the valve 17 for movement from its seat by the nozzle 25, which, under the pressure of the extinguishant, is instantly moved from its retracted position in the body in spaced relation to the outlet 14 of the bore 13, to its projected position shown in Figure 2 wherein the tip 27 of the nozzle is exposed beyond the end of the body, and the tapered peripheral surface 26 of the nozzle is in fluid-sealed engagement with the wall of the bore 13. It will be noted that the retaining element 32 acts to guide the nozzle rectilinearly in its movement and to maintain the nozzle in co-axial relationship with the bore 13 so as to insure a perfect seal between the nozzle and body when the nozzle occupies its projected position.

With the tip 27 thus exposed beyond the lower end of the body 10, the wall of the bore 13 cannot obstruct the discharge of extinguishant from the nozzle as is the case with nozzles of the fixed type which are permanently supported in the body with their tips spaced inwardly from the outlet end of the bore.

Thus, it will be clear that under the pressure in the container 43, the extinguishant will be discharged from the port 28 in the form of a finely atomized whirling spray or vapor throughout an extremely wide angle as indicated by the broken lines in Figure 2, so as to cover a much larger area than will the relatively inefficient nozzles of the fixed type heretofore proposed, which have their spraying area very materially reduced by being recessed in a supporting structure.

It will be understood that although my invention has been specifically described in connection with a pressured automatic, self-contained extinguishing unit, that the invention is equally well adapted for use in the well known water sprinkling systems controlled by fusible elements located at various points along water distributing conduits, and that therefore this disclosure and claims are to be construed broadly as covering all types of fire extinguishing units and systems.

I claim:

1. A fire extinguisher sprinkler head comprising: a support having a longitudinally tapered bore therethrough, the smaller end of which is bounded by an annular valve seat and forms a bottom outlet for a container of fire extinguishant under pressure; a valve for said outlet; a thermo-responsive element normally maintaining said valve in engagement with said seat to close said outlet, and releasing said valve to open said outlet when said element is subjected to a predetermined maximum temperature; a longitudinally tapered nozzle having a spray tip at its smaller end and being movable longitudinally in said bore; and means confining the nozzle against displacement from the larger end of said bore and co-acting with said valve when closed, to maintain the nozzle in a retracted position in the bore for movement of the nozzle by pressure of the extinguishant when said valve is released, to a projected position wherein the nozzle is sealed fluid-tight against the wall of the bore and the tip of the nozzle is exposed below said outlet so as to be free to spray extinguishant throughout an extremely wide area; said taper of said nozzle being in close proximity to the bore wall in the retracted position of the nozzle, so as to guide the nozzle substantially co-axially of the bore from retracted to projected position in order to prevent tilting of the nozzle against the bore wall in the projected position of the nozzle.

2. A fire extinguisher sprinkler head comprising: a support having a longitudinally tapered bore therethrough, the smaller end of which is bounded by an annular valve seat and forms a bottom outlet for a container of fire extinguishant under pressure; a valve for said outlet; a thermo-responsive element normally maintaining said valve in engagement with said seat to close said outlet, and releasing said valve to open said outlet when said element is subjected to a predetermined maximum temperature; a longitudinally tapered nozzle having a spray tip at its smaller end and being movable longitudinally in said bore; and a retaining element in said bore, in which a cylindrical portion of the nozzle is slidably fitted to guide the nozzle substantially co-axially against tilting movements from a retracted position when said valve is closed, to a projected position by pressure of the extinguishant when said valve is released, and wherein the nozzle is sealed fluid-tight against the wall of said bore and the tip of the nozzle is exposed below said outlet so as to be free to spray extinguishant over an extremely wide area.

3. A fire extinguisher sprinkler head comprising: a support having a longitudinally tapered bore therethrough, the smaller end of which is bounded by an annular valve seat and forms a bottom outlet for a container of fire extinguishant under pressure; a valve for said outlet; a thermo-responsive element normally maintaining said valve in engagement with said seat to close said outlet, and releasing said valve to open said outlet when said element is subjected to a predetermined maximum temperature; a longitudinally tapered nozzle having a spray tip at its smaller end and being movable longitudinally in said bore; a portion of said nozzle being reduced in diameter and externally cylindrical to define an annular stop shoulder; and a retaining ring fixed in said bore, in which said cylindrical portion of the nozzle is reciprocably mounted and rectilinearly guided during movement of the nozzle, for co-action with said stop shoulder in confining said nozzle against displacement from the larger end of said bore; said tip of the nozzle being engaged by said valve when closed, so as to maintain the nozzle in a retracted position in said bore, for movement of the nozzle by pressure of the extinguishant when said valve is released, to a projected position wherein the nozzle seats fluid-tight against the wall of said bore and the tip of the nozzle is exposed below said outlet so

4. A fire extinguisher sprinkler head comprising: a support having a longitudinally tapered bore therethrough, the smaller end of which is bounded by an annular valve seat and forms a bottom outlet for a container of fire extinguishant under pressure; a valve for said outlet; a thermo-responsive element normally maintaining said valve in engagement with said seat to close said outlet, and releasing said valve to open said outlet when said element is subjected to a predetermined maximum temperature; a longitudinally tapered nozzle having a spray tip at its smaller end and being movable longitudinally in said bore; and means confining the nozzle against displacement from the larger end of said bore and co-acting with said valve when closed, to maintain the nozzle in a retracted position in the bore for movement of the nozzle by pressure of the extinguishant when said valve is released, to a projected position wherein the nozzle is sealed fluid-tight against the wall of the bore and the tip of the nozzle is exposed below said outlet so as to be free to spray extinguishant throughout an extremely wide area; said taper of said nozzle being in close proximity to the bore wall in the retracted position of the nozzle, so as to guide the nozzle substantially co-axially of the bore from retracted to projected position in order to prevent tilting of the nozzle against the bore wall in the projected position of the nozzle.

as to be free to spray extinguishant throughout an extremely wide angle.

4. A sprinkler head for fire extinguishing units comprising: a support having a longitudinally tapered bore therethrough bounded at its smaller end by an annular valve seat; a valve having a centering teat; a thermo-responsive element normally maintaining said valve in engagement with said seat and with said teat projecting into said bore; a longitudinally tapered nozzle having a spray tip at its smaller end and being reduced in diameter for a portion of its larger end which is cylindrical to define an annular stop shoulder; and a retaining ring fixed in the larger end of said bore, and in which said cylindrical portion of said nozzle is slidably fitted to guide the nozzle substantially co-axially of the bore throughout movement of the nozzle, with said ring and stop shoulder co-acting to confine the nozzle against displacement from the larger end of said bore; said valve teat co-acting with the spray tip of said nozzle to maintain the nozzle in a retracted position in said bore when the valve is engaging said seat, against movement of the valve to a projected position when said valve is disengaged from said seat, and wherein said spray tip is exposed beyond to end of the bore and the nozzle is sealed fluid-tight against the wall of the bore to limit the projected position of the nozzle.

5. A sprinkler head for fire extinguishing units comprising: a support having a longitudinally tapered open-ended bore bounded at its smaller end by a valve seat; a valve; a thermo-responsive element maintaining said valve closed in fluid-sealing engagement with said seat; a longitudinally tapered nozzle having a spray tip at its smaller end and being mounted for movement longitudinally in said bore from a retracted position in which the nozzle is maintained by said valve when closed, to a projected position in which said nozzle is sealed fluid-tight against the wall of said bore, with the tip of the nozzle exposed beyond the end of the bore, when the valve is released from said seat; and a retaining element fixed in said bore and having a cylindrical bore in which said nozzle is slidably fitted so as to be guided co-axially of the bore and be retained against displacement from the larger end of said bore.

PETER LIM.
